[57] CLAIM

The ornamental design for a portable sink or the like, substantially as shown.

DESCRIPTION

FIG. 1 is a perspective view taken from the top, front and right side of a portable sink showing my new design;

FIG. 2 is a perspective view taken from the top, rear and left side thereof;

FIG. 3 is a bottom plan view thereof; and

FIG. 4 is a fragmentary cross sectional view taken on line 4—4 of FIG. 2.
